UNITED STATES PATENT OFFICE.

ALLEN JOHNSTON, OF OTTUMWA, IOWA.

PRESS FOR MAKING SIDE PLATES FOR SASH-PULLEY CASINGS.

994,929.

Specification of Letters Patent. Patented June 13, 1911.

Application filed August 15, 1910. Serial No. 577,321.

To all whom it may concern:

Be it known that I, ALLEN JOHNSTON, a citizen of the United States, residing in Ottumwa, in the county of Wapello and State of Iowa, have invented a new and useful Improvement in Presses for Making Side Plates for Sash-Pulley Casings, of which the following is a specification.

My object in this invention has been to produce a machine capable of manufacturing sheet metal parts requiring a series of impressions to form them, such for instance as side plates for the casings of sash pulleys, and I have endeavored by the invention to render it possible to manufacture such parts from long or continuous strips of sheet metal of a width suitable for the parts without any interruption in the manufacture or any handling of the material after it has been started into the machine.

The construction of the machine and its mode of operation are set forth in the following description and will be fully understood from such description when considered in connection with the accompanying drawings forming a part of this specification.

In said drawings, Figure 1 is a front elevation of the machine; Fig. 2 is a side elevation partly in section; Fig. 3 is a section on the line 3—3 of Fig. 1; Fig. 4 is a section on the line 4—4 of Fig. 1; Fig. 5 is a section on the line 5—5 of Fig. 2; Figs. 6 and 7 are sections on the lines 6—6 and 7—7 respectively of Fig. 5.

My machine embodies a number of sub-presses adapted to operate in succession upon the blanks and form them step by step into the shape desired. These presses are arranged side by side in a frame composed of two uprights 10, 10 connected together at the top by a cross-piece 11 and also united at the bottom by base 12 and by an intermediate plate 13. In the uprights 10 the main shaft 14 of the press is journaled. This shaft carries at one end a loose pulley 15 and a drive pulley 16 adapted to support the driving belt, and at the other end said shaft carries a fly wheel 17 and a pinion 18 meshing with the large gear 19 on a parallel shaft 20 which I denominate a cam shaft as it carries the cams by which the action of the different die presses are regulated. The main shaft between its bearings in the uprights is provided with a number of cranks 21, 22, 23, 24, and 25, each of which

furnishes the power for actuating one of the presses embodied in the machine. The first of these presses A is adapted to stamp into the metal of the strip from which the side plates are formed, a round boss or knob *a*. The second is adapted to shape the round boss formed by the first press into the cone shape *b*, thereby fitting the projection to serve as half of the bearing of the pulley in the completed casing in which the plate is used. This press I designate as B. The third press C is adapted to punch an opening *c* in the end of the cone formed by press B. The fourth press of the series is shown at D and is adapted to sever the side plate blank *d* from the strip. The final press is shown at E and its purpose is to cut up the scrap *e* severed from the ends and edges of the side plates.

Each of the cranks above mentioned carries and actuates a head in which a depending stud or pitman 30 is secured, and through such stud gives motion to the movable die carrying member 36 of the press corresponding to the crank. The head consists of a block 27 below the crank, and retaining pieces 28 located above the crank and secured to the block 27 by bolts 29. The crank is surrounded within the head by an adjusting ring 26, operable from the exterior, and adapted by changing its position to increase or diminish the throw of the crank. The stud or pitman 30 has an enlarged top 31 which is entered in a corresponding recess 32 in the block 27 and clamped therein by bolts 33 and retainer piece 33, and thereby the pitman is made to move vertically with the crank.

The position of the pitman 30 is regulated vertically by the ring 26 and its upper surface is inclined correspondingly to the wedge 34, and such wedge 34 is retained in place by a screw 35 passing through it and threaded in the block 27. While the pitman is in the position given in Fig. 4 it is adapted to transmit power from the crank 23 (which is the crank shown in said figure) to the movable die member 36 of the sub-press, and the pitman is brought to this position whenever the flattened side 39 of the cam shaft comes opposite the lever 37 as shown in said figure, and allows said lever to swing on its pivot 38 under the force of spring 41 so as to draw the pitman toward the member 36. While the pitman is in this position, the rotation of the main or crank

shaft necessarily actuates the movable die because the descent of the pitman compels it to depress the movable die member 36 and thus operate the press, but the pitman is 5 adapted to be carried into a non-operative position after each operation of the press, by the continued rotation of the cam shaft 20 whereby the flattened surface 39 moves away from the lever 37 and the latter rides 10 over and upon the rounded surface of the shaft. This causes a reversed movement of the lever, in which through the rod 40 it swings the pitman 30 away from and out of its engagement with the die member 36 as 15 indicated in the case of an adjoining pitman 30^a at Fig. 4, and holds it in that changed position until the surface 39 returns to the position of Fig. 4 and allows the lever and pitman to return to the position shown in 20 that figure. In this swinging of the pitman into and out of operative position, it will be understood that the pitman supporting head swings on its crank. It will also be noted that the pitman 30 has a hook shaped projection 42 which is engaged by the rod 40. As the rod extends through an opening in the member 36 this feature enables the pitman to lift the member 36 to its normal position after each operation. A friction 25 spring 43 is also employed to hold the movable die member in normal position between operations, and a screw 44 and bearing piece 45 are also preferably used with the spring.

30 With the exception of minor details peculiar to the dies of the presses, all the presses are identical with the one above described, all having similar heads operated by the cranks, similar pitmen carried by the heads 35 and adapted to make and break their connection with the movable die members, similar cam surfaces 39 on the cam shaft and similar levers operated by said cam surfaces and springs 41 and controlling the position of the pitmen. The cranks are 40 differently arranged around the axis of the shaft, so that the presses will operate successively in the order in which they are arranged, instead of simultaneously, so as not to draw too heavily upon the motive power 45 at any one time. The cam surfaces 39 are also timed with reference to the cranks so that they will not allow the pitmen to be in operative position at any time when operation 50 by the presses to which they belong is not desired.

55 The strip X from which the blanks are cut, is fed at proper intervals between the operations upon it, by suitable mechanism 60 of which the preferred construction is shown in the drawings. It embodies a lever 50 pivotally hung on the lower end of a vertical lever made in two parts 51 and 51^a united by a pivot 52, and swung in one direction by 65 a roller 53 bearing on a cam 54 formed on

the end of the cam shaft 20, and in the other direction by a spring 55 attached to the upper end of the lever and to a stationary pin 56. At its lower end the lever 50 bears on the strip X, and at that end is provided 70 with devices by which, when it is swung by the cam 54, it feeds the strip X forward to the extent of the length of a side plate blank. The lever 50 is pressed down on the strip by the spring 57. Coacting with the feed 75 device is a lifting lever 58, stationarily pivoted at 59, and having a foot 60 extended under the strip X, and also having its upper end extended into proximity to the cam shaft 20 and having a roller 61 bearing on the said shaft and riding over the riser 62 thereon. When the riser acts on the lever (and it does act slightly in advance of the feeding mechanism) the outer end of the foot will be raised and will lift the strip X 80 so as to free it from the boss forming dies, and thus enable the feeding mechanism to feed the strip forward.

85 The cam shaft is geared to the main shaft so that it revolves only about one-fourth as fast as the latter, and the feed actuations occur only after all the presses have operated on the strip. That is to say, all the presses operate successively and in the order of their arrangement and at different points on the strip, between the feeding operations. But the presses are located at such distance apart as permits a side plate blank to intervene between each adjacent pair of presses, thus 90 separating the points at which operations occur by the added length of the intervening blanks and preventing any injurious effect by one press upon the operation of another. As the boss forming press contracts the metal surrounding the bosses formed by it while the cone shaping press expands the metal surrounding the cone, the importance of separating the operating points in this manner 95 will be seen.

100 A spring lifter 63 is preferably employed as shown at Fig. 5 to assist in lifting the strip X after the boss forming dies have acted upon it. A guiding flange 64 is also desirable on this lifter. The dies of presses A and B need no description. The die of press C is a punching die, and embodies a punch 65 and a spring pressed positioning die 66 adapted to center the cone for the action of the punch and also an escape passage 67 for the metal removed by the punch. The dies of press D are adapted to cut the blank to the form desired, and those of press E simply sever the waste transversely. The machine is desirably provided with a clutch at 68 for starting it, and it is controlled by 110 a foot treadle 69 and a connecting rod 70.

115 I claim:—

120 1. The press for fashioning sheet metal blanks comprising a series of sub-presses, each connected to a source of power by a 125

separate transmitting device, all said transmitting devices being adapted to disconnect from the power source and to reconnect therewith automatically, means for regulating the disconnecting and reconnecting of said transmitting devices, and means for feeding a strip of metal through the presses.

2. The press for fashioning sheet metal blanks comprising a series of sub-presses 10 each connected to a source of power by a separate transmitting device, all said transmitting devices being adapted to disconnect from the power source and to reconnect therewith automatically, and means for feeding a strip of metal through the presses.

3. The press for fashioning sheet metal blanks comprising a series of sub-presses, a shaft actuating the sub-presses and having a separate eccentric for each sub-press, such 20 eccentric being so arranged that only one sub-press shall act upon the metal at a time and transmitting devices connecting said sub-presses with the eccentrics, all said

transmitting devices being adapted to disconnect from the power source and to reconnect therewith automatically, and means for feeding a strip of metal through the presses.

4. The combination in a press for manufacturing side plates for sash pulley casings from continuous strips of sheet metal, of a series of sub-presses arranged side by side in the order in which they operate upon the metal, an actuating shaft having separate eccentrics for each press, a head pivoted on each eccentric and carrying a depending pitman adapted to engage and depress the movable member of the corresponding press, means for automatically swinging all said pitmen into and out of engagement with said movable members between operations and means for feeding the strip lengthwise to the press.

ALLEN JOHNSTON.
